United States Patent

Des. 236,646
Patented Sept. 2, 1975

236,646

LIGHTING FIXTURE

Brian W. Stewart, 8862 Dorsett Drive,
Huntington Beach, Calif. 92646

Filed Mar. 12, 1974, Ser. No. 450,306

Term of patent 14 years

Int. Cl. D20—03; D26—05

U.S. Cl. D48—4 B

FIG. 1 is an isometric view of a lighting fixture embodying my new design;

FIG. 2 is a front elevational view thereof; and

FIG. 3 is a side elevational view, showing the side not shown in FIG. 1.

The sides of the fixture are mirror images of each other. The back of the fixture is plain.

I claim:

The ornamental design for a lighting fixture, substantially as shown and described.
